Primary Examiner — Richard Edgar*Assistant Examiner* — David Truong(74) Attorney, Agent, or Firm — Faegre Drinker Biddle & Reath LLP(57) CLAIM

The ornamental design for a container for food packing, as shown and described.

DESCRIPTION

The file of this patent contains at least one photograph executed in color. Copies of this patent with color photograph(s) will be provided by the Office upon request and payment of the necessary fee.

FIG. 1 is a perspective view of a container for food packing showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

BIBIGO™ is a registered trademark of CJ CHEILJEDANG CORPORATION forming part of the claimed design.
